J. B. STRUBLE

RAILWAY TRAFFIC CONTROLLING APPARATUS

Filed Feb. 23, 1922

UNITED STATES PATENT OFFICE.

JACOB B. STRUBLE, OF OAKLAND, CALIFORNIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 23, 1922. Serial No. 538,658.

To all whom it may concern:

Be it known that I, JACOB B. STRUBLE, a citizen of the United States, residing at Oakland, in the county of Alameda and State of California, have invented certain new and useful Improvements in Railway-Traffic-Controlling Apparatus, of which the following is a specification.

My invention relates to railway traffic controlling apparatus and particularly to apparatus for governing the movement of cars or trains at points where two or more tracks intersect or converge.

I will describe one form of apparatus embodying my invention, and will then point out the novel features thereof in claims.

In the accompanying drawings, Fig. 1 is a diagrammatic view showing one form of apparatus embodying my invention applied to two intersecting tracks. Fig. 2 is a diagrammatic view showing one form of apparatus for the control and operation of the derails illustrated in Fig. 1.

Similar reference characters refer to similar parts in each of the views.

Referring first to Fig. 1, the reference characters D' and D² designate two railway tracks which intersect at the point 25, and over each of which tracks traffic moves in both directions.

Alternating current for the control and operation of all of the traffic governing devices shown in the drawing is supplied by a transformer T, the primary of which is constantly supplied with alternating current from a suitable source, which is not shown in the drawing, and the secondary of which is connected with wires B and C which lead to each of the traffic governing devices.

Each track D' and D² is provided with an insulated section which extends in each direction from the point of intersection 25 and is electrically isolated from the tracks beyond by insulated rail joints 2. Each track section is provided with a track circuit comprising a source of current and a relay. Considering track D², for example, the source of current for the associated track circuit is a transformer T², the primary of which is connected with wires B and C, and the secondary of which is connected across the track rails at the right-hand end of the

section. At the left-hand end of this section is a second transformer T⁴, the primary of which is connected across the track rails of the section and the secondary of which is connected with a track relay E². It will be seen, therefore, that in accordance with usual practice the track relay E² will be energized when track D² is unoccupied within the limits of the insulated section, and de-energized when a train occupies any part of the insulated section of this track. The track circuit for track D' similarly comprises transformer T', transformer T² and track relay E'.

Track D' is provided with two derails A³ and A⁴, located on opposite sides of the intersecting point 25, and arranged to cause derailment of trains approaching the intersecting point. Track D² is similarly provided with two derails A' and A², located on opposite sides of the point of intersection 25 and likewise adapted to cause derailment of trains approaching this point. All four derails are located within the limits of the insulated track sections, and, as here shown, each derail is normally open.

Located adjacent each derail is a signal designated by the reference character S with the same exponent as that applied to the associated derail. Signal S', for example, governs the movements of trains approaching the point of intersection 25 from the left, while signal S² governs the movements of trains approaching the point of intersection from the right. Each signal, as here shown, comprises two electric lamps G and R, adapted when illuminated to indicate "proceed" and "stop," respectively.

One form of apparatus for the control of operation of each derail A is illustrated in detail in Fig. 2. Referring to this view, it will be noted that the derail is operated by a motion plate 10 containing a slot 11 which coacts with a roller 12 operatively connected with the movable point of the derail. This particular type of operating device is chosen merely for purposes of illustration, however, and is only one of several types of equivalent devices which may be employed to accomplish the same result. The motion plate 10 is shifted or reciprocated by a motor M having an armature 8 and a field

winding 9. This motor is controlled by a circuit controller F comprising two windings 5 and 6 and a pair of contact fingers 7 and 7^a. The motor is further controlled by 5 two contacts 21 and 22, which are operatively connected with the motion plate 10 and are so arranged that contact 21 is closed at all times except when the derail A is closed, and contact 22 is closed at all times except 10 when the derail is open. Winding 6 is constantly supplied with current from the power wires B and C, while winding 5 is supplied with current of one instantaneous relative polarity or the other by means of 15 wires 3 and 4. The control of the supply of current to wires 3 and 4 will be explained hereinafter with reference to Fig. 1. As shown in Fig. 2, the derail A is open. When the derail is to be closed, the relative instantaneous polarity of the current supplied to wires 3 and 4 is reversed, so that contact fingers 7 and 7^a are reversed. Current is then supplied to motor M from power wire B, through wire 16, contact 7, 20 wire 17, field winding 9, wires 18 and 18^a, contact finger 7^a, wire 19, contact 21, wire 20, and armature 8 to power wire C. When the derail A reaches its full closed position, contact 21 opens, thereby opening the circuit just traced and so de-energizing motor M. Contact 22 in the meantime has become 25 closed. When the derail A is to be again opened, the relative instantaneous polarity of the current supplied to winding 5 is again reversed, so that contact fingers 7 and 7^a are restored to the positions in which they are shown in the drawing. Current then 30 flows from power wire B, through wire 16, contact finger 7, wires 23 and 18, field winding 9 of motor M, wire 17, contact finger 7^a, wire 24, contact 22, wire 20, and motor armature 8 to power terminal C. As soon as 35 the opening movement of derail A is completed, contact 22 opens thereby de-energizing motor M, but contact 21 has closed in the meantime, so that the parts are restored to the positions in which they are shown in the drawing.

Operatively connected with the contact 40 fingers 7 and 7^a of the circuit controller F is a contact 13 which occupies one position or the other according as the contact fingers are in one closed position or the other. Operatively connected with the derail A itself, 45 that is, with the movable point of this derail, is a second circuit controller 14 which occupies one position or the other according as the derail is closed or open. Operatively connected with the motion plate 10 is a third contact 15 which occupies one position or the other according as the motion plate is in one extreme position or the other. These 50 three contacts 13, 14 and 15 are employed to govern certain parts of the apparatus shown in Fig. 1, where they appear with suitable

exponents applied to the reference characters to correspond to the exponent of the associated derail.

Referring again to Fig. 1, the control of the derails is as follows: Considering derail A', and assuming that track relay E² is energized as shown, the control wires 3' and 4' for circuit controller F' are supplied with current of normal or "derail open" polarity, through the following circuit: from power wire B, through wire 26, front point of contact 27 of relay E², wire 28, wire 3', winding 5 of circuit controller F', wire 4', wires 29 and 30, front point of contact 31 of relay E² and wire 32 to power wire C. The instantaneous relative polarity of the current thus supplied to circuit controller F' is such as to cause derail A' to be open. At the same time circuit controller F² for derail A² is supplied with current of the same relative 85 polarity through a circuit which passes from power wire B, through wire 26, contact 27, wires 28 and 32, circuit controller F², wires 4² and 30, contact 31, and wire 32 to wire C. Derails A³ and A⁴ are similarly controlled 90 by track relay E'. When this relay is energized, current flows from power wire B, through front contact 33 of relay E', wire 34 where the circuit divides, and one branch continues through wire 3³, circuit controller F³, and wire 4³, while the other branch passes through wire 3⁴, circuit controller F⁴, and wires 4⁴ and 37; the circuit then continues through wire 35, and the front point of contact 36 of relay E' to power wire C. The instantaneous relative polarity of the current thus supplied to each circuit controller F³ and F⁴ is such as to cause derails 100 A³ and A⁴ to be open.

I will now assume that a train moving 105 toward the east enters the insulated track section of track D², thereby de-energizing relay E². The control winding 5 in circuit controller F' is then supplied with current which flows from power wire B, through 110 wire 75, contacts 13⁴, 14⁴ and 15⁴ associated with derail A⁴, wire 38, contacts 15³, 14³ and 13³ associated with derail A³, wire 39, back point of contact 31 of track relay E², wires 30, 29 and 4', control winding of circuit controller F', wires 3' and 28, back point of contact 27 of track relay E², and wire 32 to power wire C. The current thus supplied to circuit controller F' is of the opposite instantaneous relative polarity, and, consequently, it causes derail A' to close. Inasmuch as the control winding in circuit controller F² is connected in multiple with the corresponding winding in circuit controller F', it follows that circuit controller F² will 120 likewise be reversed, and so will cause derail A² to close. It will be observed, however, that derails A' and A² will not close unless the contacts 13, 14 and 15 associated with the derails in track D' are all in the position 125 130

tions shown in the drawing, that is, unless derails A³ and A⁴ are both open, the motion plate for each of these derails A³ and A⁴ is in the position corresponding to the open position of the derail, and the circuit controllers for these latter derails are both in normal position. As soon as the train leaves the insulated section of track D², track relay E² again becomes energized, thereby restoring derails A' and A² to their open positions.

I will now assume that while the insulated section of track D² is unoccupied, a train enters the insulated section of track D', thereby de-energizing track relay E'. The circuits for the control windings of circuit controllers F³ and F⁴ then pass from power wire B, through contacts 13', 14' and 15' associated with derail A', wire 41, contacts 15², 14² and 13² associated with derail A², wire 42, back point of contact 36 of track relay E', wire 35, control windings of circuit controllers F³ and F⁴ in multiple, wire 34, back point of contact 33 of track relay E', wire 43, front contact 44 of track relay E², and wire 45 to power wire C. The instantaneous relative polarity of the current thus supplied to circuit controllers F³ and F⁴ is such as to cause derails A³ and A⁴ to close, but it will be observed that this can be accomplished only if derails A' and A² are open and all of the apparatus associated with these derails is in normal condition.

It will be noted that the closing circuit for derails A³ and A⁴ includes a front contact 44 of track relay E². The function of this contact is to prevent reversal of both pairs of circuit controllers F', F² or F³, F⁴ if two trains should enter the two insulated track sections at the same instant. If this should happen, the two track relays E' and E² would, of course, open at the same instant. The opening of relay E² would cause reversal of derails A' and A² in track D², but the opening of contact 44 of this relay would prevent the closing of derails A³ and A⁴ in track D'. It follows that the train on track D² will be permitted to proceed across the intersection, whereas the train on track D' will be derailed if it should attempt to proceed. As soon as the train on track D² leaves the insulated track section, derails A' and A² will open, while derails A³ and A⁴ will close, so that the train on track D' will then be permitted to proceed.

The control of the signals is as follows. Signals S' and S² are controlled in multiple by a signal relay H², whereas signals S³ and S⁴ are controlled in multiple by a signal relay H'. Signal relay H² is normally de-energized, and when in this condition the stop lamps R of signals S' and S² are both illuminated through a circuit which passes from power wire B, through wire 46, back

contact 47 of relay H², wire 48, where the circuit divides, one branch passing through wire 49, lamp R of signal S' and wire 50 to power wire C, while the other branch passes through wire 51, lamp R of signal S² and wire 52 to power wire C. Similarly, when signal relay H' is de-energized, current passes from wire B, through the back point of contact 56 of relay H', wire 57 where the circuit divides, one branch passing through wire 58, lamp R of signal S³, and wire 59 to power wire C, while the other branch passes through wire 64, lamp R of signal S⁴ and wire 61 to the power wire C.

When relay H² is energized, the stop lamp R of each signal S' and S² will be extinguished, and the proceed lamp G of each signal will be lighted by virtue of a circuit which passes from power wire B, through wire 46, contact 47, wire 53, to point 73 where the circuit divides, one branch passing through wire 54, the proceed lamp G of signal S' and wire 50 to power wire C, while the other branch passes from point 73 through wire 55, the proceed lamp G of signal S² and wire 52 to power wire C. Similarly, when relay H' is energized, the stop lamp R of each signal S³ and S⁴ becomes extinguished, and the proceed lamps G of these signals are lighted by virtue of a circuit which passes from power wire B, through contact 56 of relay H', wire 62, to point 74 where the circuit divides, one branch passing through wire 63, lamp G of signal S³ and wire 59 to power wire C, while the other branch passes from point 74 through wire 60, lamp G of signal S⁴, and wire 61 to power wire C.

The circuit for signal relay H² passes from power wire B, through wire 75, contacts 13⁴, 14⁴ and 15⁴ associated with derail A⁴, wire 38, contacts 15³, 14³ and 13³ associated with derail A³, wire 39, back point of contact 31 of track relay E², wire 30, wires 29 and 65, contacts 13', 14' and 15' associated with derail A', wire 66, contacts 15², 14² and 13² associated with derail A², wire 67, winding of relay H² and wire 68 to power wire C. It will be observed that this circuit is closed only when derails A³ and A⁴ are opened, derails A' and A² are closed and track relay E² is de-energized. In other words, relay H² will be energized only when a train has entered the insulated section of track D² and derails A' and A² have both responded to the presence of this train by closing. The energizing of relay H², of course, results in causing both signals S' and S² to indicate proceed.

The circuit for relay H' passes from power wire B, through contacts 13', 14' and 15' associated with derail A', wire 41, contacts 15², 14² and 13² associated with derail A², wire 42, back point of contact 36 of track relay E', wires 35, 37 and 76, contacts 13⁴,

14⁴ and 15⁴ associated with derail A⁴, wire 69, contacts 15³, 14³ and 13³ associated with derail A³, wire 70, winding of relay H' and wire 71 to power wire C. It will be observed that this circuit is closed only when derails A' and A² are open, derails A³ and A⁴ are closed, and track relay E' is de-energized. In other words, signal relay H' is energized only when a train has entered the insulated section of track D' and both derails A³ and A⁴ have responded to the presence of such train by closing. When relay H' is energized, signals S³ and S⁴ will give the proceed indication, as hereinbefore explained.

Although I have herein shown and described only one form of apparatus embodying my invention, it is understood that various changes and modifications may be made therein within the scope of the appended claims without departing from the spirit and scope of my invention.

Having thus described my invention, what I claim is:

25 1. In combination, two intersecting railway tracks, a normally open derail in each track, and means set into operation by a train approaching the intersection on either track for closing the derail in such track provided the derail in the other track is open.

30 2. In combination, two intersecting railway tracks, a normally open derail in each track, and means set into operation by a train approaching the intersection on either track for closing the derail in such track provided there is no train approaching the intersection on the other track.

35 3. In combination, two intersecting railway tracks, a track circuit for each track including a source of current and a track relay, a normally open derail in each track, and means set into operation by each relay when released by a train entering the corresponding track circuit for closing the derail in the corresponding track provided that the derail in the other track is open.

40 4. In combination, two intersecting railway tracks, a track circuit for each track including a source of current and a track relay, a normally open derail in each track, and means set into operation by each relay when released by a train entering the corresponding track circuit for closing the derail in the corresponding track provided that the track circuit for the other track is unoccupied.

45 5. In combination, two intersecting railway tracks, a track circuit for each track including a source of current and a track relay, a normally open derail in each track, a governing circuit for closing each derail which circuit is controlled by the track relay for the corresponding track and is closed only when such relay is de-energized,

and means for preventing closure of said governing circuit for either derail unless the derail in the other track is open.

6. In combination, two intersecting railway tracks, a track circuit for each track including a source of current and a track relay, a normally open derail in each track, a governing circuit for closing each derail which circuit is controlled by the track relay for the track in which the derail is located and is closed only when such relay is de-energized, and means for preventing said governing circuit for one derail from being closed when the track relay for the other track is de-energized.

7. In combination, two intersecting railway tracks, a track circuit for each track including a source of current and a track relay, a normally open derail in each track, a governing circuit for closing each derail which circuit is controlled by the track relay for the track in which the derail is located and is closed only when such relay is de-energized, means for preventing either of said governing circuits for closing unless the derail in the other track is open, and means for preventing said governing circuit for one derail from being closed when the track relay for the other track is de-energized.

8. In combination, two intersecting railway tracks, a normally open derail in each track, a governing circuit for each derail arranged when closed to close the derail, and means controlled by a train on either track approaching the intersection for closing said governing circuit for the derail in such track provided the derail in the other track is open.

9. In combination, two intersecting railway tracks, a normally open derail in each track, a governing circuit for each derail arranged when closed to close the derail, and means controlled by a train on either track approaching the intersection for closing said governing circuit for the derail in such track provided there is no train approaching the intersection on the other track.

10. In combination, two intersecting railway tracks, a track circuit for each track including a source of current and a track relay, a derail in each track, and means for controlling each derail by the relay for the corresponding track and one derail by the relay for the other track.

11. In combination, two intersecting railway tracks, a track circuit for at least one of said tracks including a track relay, a normally open derail in the other track, and means for preventing said derail from being closed when said track relay is de-energized.

12. In combination, two intersecting railway tracks, a derail in each track, an operating mechanism for each derail responsive to reversals of current to open and close the derail, means for normally supplying

current of opening polarity to each mechanism and for supplying current of closing polarity to either mechanism when a train is approaching the associated derail and the 5 other derail is open.

13. In combination, two intersecting railway tracks, a track circuit for each track including a normally energized relay, a derail in each track, an operating mechanism 10 for each derail responsive to reversals of current to open and close the derail, means for supplying each mechanism with current of opening polarity when the associated track relay is energized, and means for supplying each mechanism with current of closing polarity when the associated relay is de-energized provided the other derail is then open.

14. In combination, two intersecting railway tracks, a track circuit for each track including a normally energized relay, a derail in each track, an operating mechanism for each derail responsive to reversals of current to open and close the derail, means 20 for supplying each mechanism with current of opening polarity when the associated track relay is energized, means for supplying each mechanism with current of closing polarity when the associated relay is de-energized provided the other derail is open, and means for preventing the supply of current of closing polarity to the mechanism for one derail when the relay for the other track is de-energized.

15. In combination, two intersecting railway tracks, a derail in each track, a circuit controller for governing each derail and responsive to reversals of current, means for normally supplying each circuit controller 30 with current of such polarity as to open the associated derail and for supplying each circuit controller with current of the opposite polarity when a train is approaching the associated derail, and means for preventing the supply of the last-mentioned polarity to either circuit controller unless the other circuit controller is in normal position.

16. In combination, two intersecting railway tracks, a normally open derail in each 40 track, means controlled by a train approaching said intersection on either track for closing the derail in such track provided the derail for the other track is open, a signal for each track, and means controlled by a train approaching the intersection on either track for clearing the signal for such track if the derail for such track is closed and the derail for the other track is open.

17. In combination, two intersecting railway tracks, a derail in each track, a signal 50 for each track, and means controlled by a

train approaching the intersection on either track for clearing the signal for such track if the derail for such track is closed and the derail for the other track is open. 65

18. In combination, two intersecting railway tracks, a derail in each track, a signal for each track, contacts operated by said derails, and a circuit for each signal including a contact on the derail in the same track 70 which is closed only when the derail is closed and a contact on the other derail closed only when the derail is open.

19. In combination, two intersecting railway tracks, a track circuit for each track, 75 a derail in each track, and a signal for each track controlled by the corresponding track circuit and by both derails.

20. In combination, two intersecting railway tracks, a track circuit for each track, 80 a derail in each track, a signal for each track, and means for preventing each signal from indicating proceed unless the corresponding track circuit is occupied and the corresponding derail is closed and the other 85 derail is open.

21. In combination, two intersecting railway tracks, a track circuit for one track, a signal for the same track, a derail for the other track, and means for controlling said 90 signal jointly by said track circuit and by said derail.

22. In combination, two intersecting railway tracks, a derail for each track, a signal for one track, a relay for said signal arranged to cause the signal to indicate stop or proceed according as the relay is de-energized or energized, and a circuit for said 95 relay controlled by said derails and closed only when the derail in the track associated 100 with said signal is closed and the other derail is open.

23. In combination, two intersecting railway tracks, a signal for one track, a derail for the other track, a relay for said signal 105 arranged to cause the signal to indicate proceed or stop according as the relay is energized or de-energized, and a circuit for said relay controlled by said derail and closed only when the derail is open. 110

24. In combination, two intersecting railway tracks, a track circuit for one track, a signal for the same track, a derail for the other track, a relay, means for causing said signal to indicate proceed or stop according as the relay is energized or de-energized, and means for controlling said 115 relay by said track circuit and by said derail.

In testimony whereof I affix my signature.

JACOB B. STRUBLE.
